UNITED STATES PATENT OFFICE

169,959

MILK BOTTLE

Royden A. Blunt, Baltimore, Md.

Application July 24, 1951, Serial No. 16,008

Term of patent 14 years

(Cl. D53—6)

To all whom it may concern:

Be it known that I, Royden A. Blunt, a citizen of the United States, residing at Baltimore, Maryland, have invented a new, original, and ornamental Design for a Milk Bottle, of which the following is a specification, reference being had to the accompanying drawing, forming a part thereof:

Figure 1 is an elevation of a milk bottle showing my new design;

Figure 2 is a further elevation of the bottle turned with respect to the position of Figure 1; and

Figure 3 is a top plan view of Figure 1.

The dominant features of my design reside in the portions shown in full lines.

This application is a continuation-in-part of my application Serial No. D. 14,943, filed April 24, 1951, now abandoned.

I claim:

The ornamental design for a milk bottle, substantially as shown and described.

ROYDEN A. BLUNT.
